BILLFOLD

Leah L. Gardner, University City, Mo.

Application July 11, 1941, Serial No. 401,903

1 Claim. (Cl. 150—35)

This invention relates to bill folds.

The invention is shown embodied in an elongated bill fold foldable transversely midway of its ends between the adjacent inner ends of relatively short inner pocket walls. The enclosure, constituting a part of the present invention, is detachably secured to one of the relatively short pocket walls and preferably extends to the end of the bill fold, although it may be secured to the short pocket wall in other positions if preferred.

Objects of the invention are to provide an enclosure in the nature of an identification card case or coin purse adapted to receive and retain cards and coins or other articles, and having a width no greater than the width of the bill fold and a length no greater than one-half the length of the bill fold so that the bill fold may be folded transversely along the usual fold line midway between its ends to cover and enclose the enclosure when the latter is attached to the bill fold; to provide means for detachably securing the enclosure to an exposed short pocket wall in a relationship in which the enclosure is within the bill fold when the latter is folded; and to provide a tab in connection with the concealed wall of the enclosure arranged to fold against the exposed wall thereof and to be detachably secured thereto to prevent the contents of the enclosure from working out or becoming lost.

Another object of the invention is to provide means for securing the enclosure to a short pocket wall of the bill fold in a manner to strengthen and reinforce the same and to resist undesired crumpling and bending of the bill fold.

Other objects will appear from the following description, reference being made to the annexed drawings, in which—

Fig. 1 is a side elevation of a folded bill fold having the present invention included therein.

Fig. 2 is an inner side elevation of the bill fold showing an enclosure element of the present invention attached thereto.

Fig. 3 is an inner side elevation of one end portion of the bill fold showing the fastener elements attached to the short pocket wall.

Fig. 4 is a side elevation of an enclosure element included in the present invention.

Fig. 5 is an end elevation of the enclosure device shown in Fig. 4.

Fig. 6 is an enlarged cross-sectional view on the line 6—6 of Fig. 3.

Fig. 7 is an enlarged cross-sectional view on the line 7—7 of Fig. 2.

Fig. 8 is a side elevation of a folded bill fold of a different type from that shown in Fig. 2 and

having a coin purse detachably secured thereto.

Fig. 9 is an inner side elevation of the bill fold of Fig. 8, showing a coin purse attached thereto.

Fig. 10 is an inner side elevation of one end portion of the bill fold of Fig. 9, showing the fastener elements attached to the short pocket wall.

Fig. 11 is a side elevation of the coin purse detached from the bill fold.

Fig. 12 is an end elevation of the coin purse in open position.

The bill fold embodying the invention shown on sheet 1 of the drawings is made substantially the same as the bill fold proper disclosed in my prior Patent No. 2,182,867. However, the present invention is not restricted to use in connection with that specific type of bill fold, and it is plain that the invention may be used in different types of bill folds.

The bill fold proper comprises an elongated outer wall 1 having attached thereto at one end relatively short pocket forming walls 2 and 3 terminating short of the transverse fold line 4 midway between the ends of the bill fold. If desired, similar short pocket forming walls may be attached to the opposite end of the bill fold terminating short of the transverse fold line 4. In the specific type of bill fold shown, a tab 5 is integral with the lower longitudinal edge of the wall 1 and has an interlocking engagement 6 with the wall 2. As shown in Fig. 2, this arrangement is provided at each end of the bill fold. A panel 7 extends into the two short pockets and spans the space between them and cooperates with the inner walls of said short pockets to form an elongated pocket 8.

The enclosure device adapted to be detachably secured to the short pocket wall 2 comprises walls 9 and 10, preferably of equal length and width and integrally or otherwise connected along their lower edges by a flexible hinge 11. Between the walls 9 and 10, one or more pairs of walls 12, 13, 14 and 15 are secured. While I have shown four pairs of these walls, it is apparent that the number of said walls may be increased or reduced as desired without departure from this invention. Further, it will be apparent that these enclosed walls may be omitted entirely if desired and a single wall 16 attached to one of the walls 9 or 10 along its lower and end edges, leaving the upper edge unattached to said wall 9 or 10, thereby providing a pocket between the wall 16 and the wall 9 or 10 to which it is attached. Each pair of walls 12, 13, 14 and 15 are attached together along their end and lower longitudinal edges to provide a pocket 17 between each pair

of said walls. The pocket 17 is open at the top to facilitate insertion and removal of identification cards or analogous devices. Preferably, the walls 12, etc., and the wall 16 are made of resilient spring material such, for instance, as isinglass, Celluloid, or the like, so that said walls will function not only as pocket forming walls within the enclosure, but also function to retain or restore the enclosure to its straight flat condition when it is bent. Further, when the device is attached to the bill fold, it cooperates directly therewith to prevent undesired crumpling and bending of the bill fold without interfering with the folding of the latter along the transverse line 4 midway between its ends.

As shown in Fig. 7, the pair of walls 12 and the pair of walls 15 are attached together by a flexible hinge device 18, and the adjacent pairs of walls 13 and 14 are attached together by a flexible hinge device 19 seating against the hinge 18. Both hinges 18 and 19 are attached to the hinge 11 by a longitudinal row of stitches 20, or otherwise.

A tab 21 is attached to the upper edge of the wall 9 by a hinge 22 above the plane of the upper edges of the inner resilient walls. The tab 21 is foldable over the upper edges of the inner walls and of the wall 10 and downwardly against the exposed surface of the wall 10. A fastener 23 attached to the tab 21 is arranged to engage a cooperating fastener 24 attached to the wall 10 and thereby hold the enclosure device sealed or closed. The fastener device 23 may easily be engaged with and disengaged from the element 24 to close or to open the enclosure.

At least two fastener elements 25 and 26 are secured to one of the exposed short pocket walls. As shown in Fig. 3, the fastener element 25 is attached to the wall 2 and the fastener element 26 is attached to the interlocking tab 5. These fastener elements may be located elsewhere in connection with the short pocket wall. A pair of equally spaced fastener elements 27 and 28 are attached to the wall 9 of the enclosure device for detachable engagement with the fastener elements 25 and 26, respectively. The enclosure device is shown attached to the bill fold in Fig. 2 in a location and arrangement in which the outer end of said device is approximately even with the adjacent end of the bill fold and in which the inner end of said device is spaced far enough from the transverse fold line 4 to enable the bill fold to be folded along said line to a position in which the ends of the bill fold and of the enclosure device are approximately even. It will be noted that the enclosure device is of slightly less width than the outer wall 1 of the bill fold and is of approximately the same width as the short pocket wall 2 to which it is attached. When the enclosure device is attached to the bill fold, it strengthens, stiffens and reinforces the bill fold, the resilient walls 12, etc., cooperating to prevent crumpling or rolling or undesired bending of the bill fold and functioning to restore the bill fold to flat form when the bill fold is not subject to external pressure.

As shown in Figs. 6 and 7, the fastener elements 25 and 26 extend through the wall 2 and tab 5, respectively. A lining 29 is secured to the inner surface of the wall 2, and is attached to the lower margin of the wall 3 by a line of stitches 30. The lining 29 also covers the interlock 6 so that cards and other articles may be slipped into and from the pocket provided by the walls 2 and 3 without

contacting or abutting against the fastener elements 25 and 26.

The bill fold shown on sheet 2 of the drawings is generally of the type disclosed in Prince A. Gardner Patent No. 2,007,469, July 9, 1935. It comprises an elongated outer wall 31 having attached thereto at one end relatively short pocket forming walls similar to the walls 2 and 3 and including an exposed wall 32. The opposite end of the bill fold includes a short pocket comprising a frame 33 and a resilient panel 34 composed of spring material such, for instance, as isinglass, Celluloid, or the like, functioning to retain or restore the bill fold to its straight or flat condition after it has been bent. The bill fold is foldable transversely along a line 35 midway between its ends and between the two short pockets. In this form of the invention, a coin purse is provided comprising a wall 36 and a wall 37 attached to the lower edge of the wall 36 by a hinge device 38. The walls 36 and 37 are connected at their ends by folding walls 39 to provide a purse or receptacle open only at the top. A tab 40 is connected with the wall 36 by a hinge device 41 so that, when the coin purse or receptacle is closed and the two walls 39 are folded inwardly, the tab 40 may be extended along the wall 37 and detachably secured thereto by engageable and releasable fastener devices 42 and 43.

In the arrangement shown, the fastener device 42 is attached to the tab 40 and the fastener device 43 is attached to the wall 37. In this arrangement, a number of fastener elements 44 are attached to the wall 32 and a fastener element 45 is attached to the interlocking tab 46 which is interlocked with the wall 32 in the same manner that the tab 5 is interlocked with the wall 2. An equal number of fastener elements 47 are secured to the wall 36 for releasable engagement with the fastener elements 44 and 45, so that the coin purse may be secured to the wall 32 and tab 46 in the position shown in Fig. 9. As there shown, the coin purse is within the area of the end portion of the bill fold, the outer end of the coin purse being approximately even with the adjacent end of the bill fold, the lower edge of the coin purse being approximately even with the lower edge of the bill fold, the upper edge of the coin purse being substantially below the upper edge of the wall 1 and approximately even with the upper edge of the wall 2, and the inner end of the bill fold terminating laterally beyond the fold line 35. Arranged in this way, the coin purse strengthens and reinforces the end of the bill fold to which it is attached, does not interfere with the folding of the bill fold along the transverse line 35, and directly cooperates with the element 34 to prevent rolling or crumpling of the bill fold and to straighten the same when released from external pressure. The coin purse may be easily attached to and detached from the bill fold and used as a separate receptacle or purse when desired, leaving the bill fold free to be used as such or for all of its intended purposes, just as the bill fold shown on sheet 1 of the drawings may be used for its intended purposes when the enclosure device there shown is detached for separate use.

Both modifications of the invention disclosed are embodied in a foldable and unfoldable bill fold having inner and outer wall elements provided with a transverse fold line about midway of their ends so that the two end portions of the bill fold may swing to folded and unfolded positions. In the bill folds in which the modifica-

tions of the invention are shown, there are similar short walls 2 and 32 each having three edges thereof attached, respectively, to one end and to the lower longitudinal edge of both of said wall elements and to the upper longitudinal edge of the inner wall element only. The separate bendable enclosure device in each modification is a unitary member composed indispensably of a rear wall, a front wall, a flexible hinge integral-
ly connecting said rear and front walls along one edge thereof for swinging movements of said rear and front walls to and from superimposed position, and a tab having flexible hinge connection with the edge of said rear wall opposite from said hinge for swinging movements to and from superimposed position against the exposed front surface of said front wall when said rear and front walls are superimposed. In the arrangement shown in Fig. 5, there is at least one pair of walls 12 or 13 or 14 or 15 attached to said hinge 11 between said front and rear walls and have their end edges and one longitudinal edge attached together to form a pocket between said front and rear walls and wholly within the enclosure. In the specific form shown in Fig. 12, there are folding walls 39 connecting the ends of the front and rear walls of the enclosure, and providing a purse or receptacle open only at the top. In both forms there are fastener elements attached to the short wall and to the rear wall, respectively, for releasably engaging each other and thereby supporting the enclosure wholly on the outer side of the short wall of the bill fold and also preventing displacement of said enclosure in any direction along said short wall of the bill fold both when the bill fold is folded and unfolded. Each enclosure has fastener elements attached to its front wall and its tab, respectively, for holding the tab against the front wall in position to close the enclosure; and in the embodiment of Fig. 5, the tab also closes the pocket that is attached to the hinge within the enclosure.

From the foregoing, it will be apparent that this invention attains all of its intended objects and purposes efficiently and satisfactorily. It may be made and sold at permissible cost and varied in other particulars than those specifically mentioned without departure from the nature and principle of the invention.

I claim:

In a bill fold having an elongated outer wall, wall elements attached to the ends and lower longitudinal edge of said outer wall and cooperating therewith to form an elongated bill fold having a transverse fold line about midway of its ends, and a relatively short wall attached to one end and to the lower longitudinal edge of said outer wall and said wall elements and also attached to one of said wall elements along its upper edge only and forming one wall of a pocket closed along its upper and lower sides and outer end and having an open inner end adjacent to and toward said fold line; a fastener element attached to one margin of said short wall, another fastener attached to said short wall adjacent to an opposite margin, an enclosure comprising two walls having flexible integral hinge connection along one edge and having a width about equal to the width of said short wall, fastener elements attached to one wall only of said two walls for engaging said first named fastener elements and thereby holding said enclosure against said short wall in a position in which the inner end of said enclosure is short of said fold line and in which said short wall entirely covers one side of said enclosure, leaving the bill fold free to fold transversely along said fold line and wholly enclose said enclosure between the folded portions of said bill fold, and detachable means on said two walls of said enclosure for holding the same flatwise and closed as desired during the time that said enclosure is attached to said bill fold.

LEAH L. GARDNER.
